United States Patent Office.

MINOT S. SCOFIELD, OF STAMFORD, CONNECTICUT.

Letters Patent No. 99,009, dated January 18, 1870.

IMPROVEMENT IN HAND-BARROWS.

The Schedule referred to in these Letters Patent and making part of the same.

To all whom it may concern:

Be it known that I, MINOT S. SCOFIELD, of Stamford, in the county of Fairfield, and State of Connecticut, have invented a new and useful Improvement in Hand-Barrows; and I do hereby declare that the following is a full, clear, and exact description thereof, which will enable others skilled in the art to make and use the same, reference being had to the accompanying drawings, forming part of this specification, in which—

Figure 1 is a top or plan view of my improved hand-barrow.

Figure 2 is an end view of the same, showing it applied to a barrel.

Similar letters of reference indicate corresponding parts.

My invention has for its object to furnish an improved hand-barrow, designed for use in handling barrels, boxes, and other packages, and which shall be so constructed that it will adjust itself to various-sized packages; and

It consists in the hand-barrow constructed as hereinafter more fully described.

A are the side bars of the hand-barrow, which may be made larger or smaller, according to the size and weight of the packages, for lifting which they are designed to be used.

The side bars A of the hand-barrow are connected to each other by the bars B, which should be placed

at such a distance apart that the barrow may be placed over the barrel or other package to be lifted.

In the middle parts of the side bars A, in such positions as to bear against the barrel or other package to be raised, are inserted one or more spikes, C, as shown in figs. 1 and 2.

The bars B are made in two parts, jointed or hinged to each other at or near the centre of said bars.

The ends of the bars B are rigidly attached to the side bars A.

The joint in the bars B not only allows the barrow to adjust itself to various-sized packages, but it also prevents the side bars from being turned by the downward pressure, upon the spikes C, of the package being raised and carried, thus enabling the barrow to clasp the package, and hold it securely.

Having thus described my invention,

I claim as new, and desire to secure by Letters Patent—

An improved hand-barrow, formed by the combination of the jointed or hinged bars B and spikes C with the side bars A, substantially as herein shown and described, and for the purpose set forth.

The above specification of my invention signed by me, this 10th day of November, 1869.

MINOT S. SCOFIELD.
